CARPET SWEEPER

Carl C. Parrish, Shelbyville, Ind., assignor to
Porter Steel Specialties, Shelbyville, Ind., a co-
partnership composed of Hester Porter Fuller,
George M. Parker, and Parrish Fuller

Application May 5, 1941, Serial No. 391,851

2 Claims. (Cl. 15—41)

The object of my invention is to provide efficient means by which dust pans of a carpet sweeper of the rotary-brush, hand-operated type may be readily operated to discharge their contents, the construction being such that the exposed operating element, though readily accessible, will be inconspicuous and cannot be contacted against furniture, and such that it can be incorporated in a sweeper at low cost.

The application is a continuation, in part, of my application Serial No. 317,650, filed February 7, 1940.

The accompanying drawings illustrate my invention.

Fig. 1 is a perspective view of an embodiment of my invention;

Fig. 2 an end elevation with one of the external cover plates removed;

Fig. 3 a fragmentary plan in partial horizontal section;

Fig. 4 a transverse section on line 4—4 of Fig. 1 with the pan shown in dumped position;

Fig. 5 a fragmentary section on line 5—5 of Fig. 4;

Fig. 6 a perspective view of another embodiment of my invention;

Fig. 7 an end elevation (with one end plate removed) of the form shown in Fig. 6;

Fig. 8 a section in the plane of line 8—8 of Fig. 6; and

Fig. 9 a fragmentary horizontal section of the form shown in Fig. 6.

In Figs. 1 to 5 of the drawings 10 indicates the usual end wall of the main casing or shell of a sweeper. Formed in the outer vertical face of this end wall is a groove 11 which communicates at its outer end with a slot or groove 12 formed in the upper face of the top wall 13 of the casing parallel with the side wall 14 of the casing.

Where the top wall of the casing is of wood, the slot or groove 12 conveniently extends through the top wall and is covered by an ornamental plate 16 medially depressed to form a channel 17, the outer end of which communicates with groove 11 and the inner end of which is formed into a thumb pocket 18. Journalled in groove 11 is a rock shaft 20 provided at its outer end with an operating arm 21 adapted to lie in channel 17 when the rock shaft is in its normal position. The free end of arm 21 is conveniently widened to partially fill the thumb pocket but of such size that an operator may readily insert a thumb or finger into the pocket under the free end of the arm so as to readily raise it.

The inner end of rock shaft 20 is provided with

5 an arm 25 projected inwardly through perforation 26 in the end wall at the inner end of groove 11 and adapted to engage under the apex of the pan spring 26' of usual form, the free ends of said pan spring pivotally engaging the heels of the dust pans 27—27 in an ordinary manner. The dust pans are pivotally mounted between the end walls of the casing on pivots 28—28.

10 Rock shaft 20 is held in groove 11 by suitable retaining strips 29 or double pointed tacks 30.

The operating arm 21 of rock shaft 20 is so formed that, when in its normal pan closed position, it will lie flush with the upper surface of the top wall of the casing.

15 The construction described is such that it may be manufactured at very low cost and the operating arm, under normal working conditions, is so positioned that it cannot come into contact with any furniture.

20 In the form shown in Figs. 6 to 9 inclusive, the construction is very much the same and corresponding parts are designated by the same reference numerals. In this form groove 11 is continued, at its outer end, through the side wall 10' and the operating arm 21' of rock shaft 20 normally lies alongside said side wall immediately above the usual bumper band or guard rubber 40.

25 30 It will be readily understood that while I have illustrated embodiments of my invention in a sweeper having end walls of appreciable thickness, such, for instance, as plywood commonly used in the art, a metal end wall in which an appropriate receiving groove for the rock shaft may be formed by distortion of the metal, would be within the scope of my invention.

35 The operating arm may be of quite appreciable length so that pan dumping will require the exertion of very little force so that it may be readily manipulated by the most delicate fingers.

40 I claim as my invention:

45 1. A carpet sweeper having a casing comprising end walls, side walls, and a connecting top, with one end wall provided with a groove formed in the outer face of said end wall and extending from about the medial plane of the casing outwardly toward a side wall, a channel formed in the upper surface of the top wall of the casing substantially at right angles to said groove and communicating at its outer end with said groove, a rock shaft journalled in said groove and provided, at its inner end, with an inwardly projecting arm extending through the end wall of the casing and provided at its outer end with an op-

erating arm nestable in said channel in the upper face of the top of the casing, means retaining said rock shaft in said groove, dust pans movably mounted in the casing, and means connecting the said inwardly projected arm of the rock shaft with said dust pans, said parts being so related that the operating arm will be submerged in the channel when the pans are in dust-receiving positions.

2. A carpet sweeper having a casing comprising, end walls, side walls, and a connecting top with one end wall having a groove formed in the outer face of said wall and extending from about the medial plane of the casing outwardly toward a side wall, a rock shaft journaled in said groove

10 and provided at its inner end with an inwardly projecting arm extending through the end wall of the casing and provided at its outer end with a manually-accessible manipulating arm, means retaining said rock shaft in said groove, dust pans movably mounted in the casing, and means connecting said inwardly projected arm of the rock shaft with the dust pans, the two arms of the rock shaft being so related that, when the pans are in dust-receiving positions, the manipulating arm will lie at least as low as the exposed face of the top of the casing with its free end directed toward the opposite end wall.

CARL C. PARRISH.
